UNITED STATES PATENT OFFICE.

JOHN E. MUHLFELD, OF SCARSDALE, NEW YORK, ASSIGNOR TO LOCOMOTIVE
PULVERIZED FUEL COMPANY, A CORPORATION OF DELAWARE.

FURNACE FOR BURNING PULVERIZED FUEL.

1,262,546.

Specification of Letters Patent.

Patented Apr. 9, 1918.

Application filed December 2, 1913. Serial No. 304,192.

To all whom it may concern:

Be it known that I, JOHN E. MUHLFELD, of Scarsdale, in the county of Westchester and State of New York, have invented a 5 certain new and useful Improvement in Furnaces for Burning Pulverized Fuel, of which improvement the following is a specification.

My invention, relates more particularly to 10 means for burning combustible matter in a comminuted or finely pulverized state, in the fireboxes of steam boilers, particularly locomotive boilers, and in connection with heating furnaces of other descriptions, and 15 its object is to provide means which shall be readily and inexpensively applicable in connection with furnaces or fireboxes of the ordinary construction, for supplying fuel of such character and air, in proper proportions, to a furnace, and enabling its thorough 20 and effective combustion to be carried on therein.

To this end, my invention, generally stated, consists in the combination, with a 25 main or final furnace chamber, of a preliminary furnace chamber, located exterior and adjacent to the final furnace chamber and communicating therewith, and constituting a preliminary fuel treatment space, in 30 which the fuel is commingled with air and gasified or partially consumed prior to its complete combustion in the final furnace chamber.

The improvement claimed is hereinafter 35 fully set forth.

In the accompanying drawings: Figure 1 is a vertical longitudinal central section through a locomotive boiler firebox, illustrating an application of my invention; 40 Fig. 2, a horizontal section through the preliminary furnace chamber, on the line $a-a$ of Fig. 1; Fig. 3, a section, taken similarly to Fig. 1, illustrating a structural modification; Fig. 4, a partial horizontal section, on 45 the line $b-b$ of Fig. 3; and, Fig. 5, a section, taken similarly to Figs. 1 and 3, illustrating another structural modification.

Referring first to Figs. 1 and 2, my invention is exemplified as applied in connection 50 with a main or final furnace chamber, which is shown as a locomotive boiler firebox of one of the present standard types, and is indicated, as an entirety, by the reference symbol A, from which chamber the products of

combustion of fuel burned therein are conveyed through a plurality of fire tubes, B, in the waist, C, of the boiler, to a smoke box and stack, (not shown) at its opposite end, in the ordinary manner, in which the parts enumerated coöperate to produce a draft in 60 the firebox.

In the practice of my invention, I provide, at the bottom of the firebox, a floor, 1, of fire brick or other suitable refractory material, the ordinary grates and ash pan which are 65 used for burning solid fuel not being necessary or applicable. The floor may be located at any desired level, relatively to the bottom of the firebox, as may be best suited to the depth of the latter, being herein 70 shown as set some distance below the mud ring, a' , upwardly extending side and end walls, 1^a , of fire brick, forming a closure for the intervening space. In fireboxes of greater depth it may lie in or near the plane 75 of the bottom of the mud ring.

A preliminary chamber, 2, of fire brick or other suitable refractory material, is properly supported exterior and adjacent to the final furnace chamber or firebox, A, being, 80 in this instance, located below the mud ring, and extending rearwardly and horizontally from the back head of the boiler. The form, in transverse section, of the preliminary chamber, is not an essential of my invention, 85 and it may be of rectangular, circular or elliptical transverse section, as preferred, being, in this particular instance, variable within the discretion of the constructor, or as may be best suited to accommodate adjacent members of the locomotive on which it is installed. The preliminary chamber is open at its front end to the firebox, below the mud ring, either partially, as shown, or throughout its full width. 95

Bodies or columns of pulverized fuel are delivered into the rear end of the preliminary chamber, 2, either by being forced thereinto by a fan or pressure blower, or by being drawn thereinto by induced draft, 100 through one or more conduits, 3, any desired number of which may be applied, and one being shown in Fig. 2. The conduit or conduits, 3, is or are passed through an opening or openings, 3^a , which may be closed by 105 a plate or plates, 3^b , in the rear wall of the preliminary chamber, and are adapted for the introduction of a proper volume of air

with the fuel. The top, side, and rear walls of the preliminary chamber are covered by layers, 4, of a material which is a non-conductor of heat, the non-conducting covering 5 being inclosed in a casing, 4^a, of sheet or plate metal.

A slag receptacle, 5, which is open at its top to the fire box, is suspended below the floor, 1, thereof, at its rear end, and is provided with an air inlet, 5^a, controlled by a door, 5^b, through which a regulated supply of air may be admitted to the firebox.

In the operation of a furnace in connection with which a preliminary chamber substantially as above described, is applied, the mixture of pulverized fuel and air which is delivered, through the conduit, 3, to the preliminary chamber, 2, is commingled, in proper proportions, with air, ignited, and its 20 preliminary combustion effected therein, it being partially consumed or gasified in said chamber, and the gaseous products of combustion passing therefrom into the main or final furnace chamber, A, in which complete combustion is effected. The preliminary chamber becomes highly heated, and the fuel and air supplied thereto are thoroughly commingled and preheated before being completely consumed in the final furnace chamber.

The structural modification shown in Figs. 3 and 4 is more particularly designed for application in connection with deep and narrow fireboxes, and while according in 35 operative principle with that first described, differs structurally therefrom, in the particular that the preliminary chamber, 2, is located above the level of the bottom of the final furnace chamber, A, and communicates 40 therewith through the fire door opening, b', through which the products of combustion are delivered into the final furnace chamber. Three fuel supply conduits, 3, are shown as leading into the preliminary chamber, their outlets converging in the direction of the discharge opening, b', thereof, but one or a greater number may be applied as may be considered preferable under structural and operative conditions.

Fig. 5 illustrates another structural modification in which two preliminary chambers, 2, and 2^a applied in connection with the main or final furnace chamber, A, one of them, 2^a, being located above, and the other, 2, below, the firing deck of the locomotive, and being preferably, as shown, connected, adjacent to the final furnace chamber, by a conduit, 6, of refractory material, one or more of which may be used as desired. The 60 lower preliminary chamber is open at its front end to the final furnace chamber, as in the instance first described, and shown in Figs. 1 and 2, and the upper chamber communicates with the final furnace chamber 65 through the fire door opening, as in Figs. 3

and 4. As in the preceding cases, any desired number of fuel supply conduits may be led into each of the preliminary chambers.

The novel and characteristic feature of my invention consists in a substantial increase of the length and volume of the combustion space of a furnace, and more effective utilization thereof, by the provision of an independent communicating external preliminary chamber, in which the fuel and air are commingled in proper proportions, and preliminary combustion is effected, and by means of which the entire volume of the final furnace chamber or furnace proper in which complete combustion is effected, 80 is rendered available for the burning of the fuel and gases. A feature of special advantage is that of economy of construction, as the preliminary chamber may be applied, as a separate structure, in connection with 85 existing furnaces, at materially less cost than that of reconstructing and enlarging the main furnace.

It will be observed that the preliminary chamber in the arrangement shown in the drawings has the fuel supplied thereto through a nozzle which directs the fuel toward the opening between the preliminary chamber and the firebox, this being the preferred construction because the travel of the fuel carried along by the gaseous medium through said preliminary chamber may then enter the firebox without serious obstruction such as might precipitate some of the pulverized material. By making the preliminary chamber as shown of small cross-sectional capacity in relation to the size of the firebox or combustion space into which it opens, the flow through the preliminary chamber will be relatively more rapid helping to hold the fuel in suspension and then when it reaches the larger area of the combustion space or firebox its flow or velocity will be retarded so that the air supplied for final combustion will have better opportunity to become commingled with the fuel and more complete combustion and efficient operation will be obtained. The velocity of flow through the preliminary chamber will vary, of course, with the dimensions of 115 the same so that if it be made of substantially less cross-sectional area, it will operate primarily as a mixing or fuel treatment space for obtaining thorough commingling of the air and fuel, leaving the combustion 120 to be mainly accomplished in the firebox itself.

I claim as my invention and desire to secure by Letters Patent:

1. In an apparatus for feeding and burning pulverized fuel, the combination of a main furnace chamber, two preliminary treatment chambers located exteriorly of and adjacent to the main furnace chamber and communicating at their forward ends 130

with said main furnace chamber, means for admitting a mixture of air and fuel to the rear ends of said preliminary treatment chambers, and a gas conduit connecting said 5 preliminary treatment chambers at a point intermediate their respective extremities.

2 In an apparatus for feeding and burning pulverized fuel, the combination of a main furnace chamber, a preliminary treatment 10 chamber having communication at its forward end with the main furnace chamber, a plurality of openings at the rear end of said preliminary treatment chamber, means for supplying a mixture of fuel and air under 15 pressure through each of said openings, the currents of fuel and air being directed to converge and intermix at the point of communication between the said preliminary treatment chamber and the main furnace 20 chamber.

3. A pulverized fuel burning apparatus comprising in combination a means of relatively small capacity for introducing pulverized fuel, a preliminary expansion chamber 25 into which the fuel is introduced, and which is provided with means for admitting air at the place where the fuel is admitted, and in which the fuel is preliminarily mixed and treated, said preliminary chamber being 30 also provided with an outlet, and a relatively large combustion chamber into which the said outlet of the preliminary chamber opens, said combustion chamber being provided with a waste outlet in its bottom and 35 with an exhaust means communicating with the upper part thereof.

4. A pulverized fuel burning apparatus comprising in combination a means of relatively small capacity for introducing a mixture 40 of pulverized fuel and air, a preliminary expansion chamber into which the mixture of fuel and air is introduced and which is provided with means for admitting additional air at the place where the fuel is admitted and in which the fuel is preliminarily 45 mixed and treated, said preliminary chamber being also provided with an outlet, and a relatively large combustion chamber into

which said outlet opens, said combustion chamber having means for admitting additional air therein, and a waste outlet at the bottom thereof and means communicating with the upper part of the chamber for inducing a draft therein. 50

5. In an apparatus for feeding and burning pulverized fuel in suspension, the combination with a firing chamber and means for inducing draft therein and a preliminary treatment chamber communicating with said firing chamber, of means for introducing a 60 mixture of the fuel and a combustion supporting vehicle into said treatment chamber and for simultaneously inducing atmospheric air therein in volumes substantially proportionate to the quantities of the mixture delivered but insufficient to effect complete combustion, and means whereby the draft in the firing chamber induces additional quantities of atmospheric air into said firing chamber, the point of inlet in the firing 65 chamber being adjacent to the end of the preliminary chamber. 70

6. A pulverized fuel burning apparatus comprising the combination with a steam boiler, a firing chamber therefor having a 75 waste outlet in the bottom and means forward of the chamber and communicating with the upper part thereof for creating a draft to draw the gases of combustion through the firing chamber, of a preliminary 80 treatment chamber having an outlet opening into the firing chamber, means for introducing a mixture of fuel and air into said treatment chamber, an opening near the same whereby the flow of an additional supply 85 of a combustion supporting medium is drawn into the preliminary treatment chamber and added to said mixture as it enters said chamber, but in quantities insufficient to effect complete combustion, and means for 90 admitting an additional supply of air into the firing chamber.
